UNITED STATES PATENT OFFICE.

LOUIS ILLMER, OF CORTLAND, NEW YORK.

FUEL PUMP FOR INTERNAL-COMBUSTION ENGINES.

Application filed April 19, 1918. Serial No. 229,556.

To all whom it may concern:

Be it known that I, LOUIS ILLMER, a citizen of the United States, and a resident of Cortland, in the county of Cortland and State of New York, have invented a new and useful Improvement in Fuel Pumps for Internal-Combustion Engines, of which the following is a specification.

My invention relates to high pressure injection pumps for liquid fuel engines, and its object is to provide a device which, without the use of compressed air, will effect a high velocity discharge through a practical size of nozzle opening regardless of the engine speed, and will also effect a sharp cut-off action which will insure against any drip formation to the discharging spray being injected into the engine cylinder.

Another object is to provide a liquid fuel injecting device for high pressure oil engines which possesses regulatable means for varying the amount of fuel to be injected into the cylinder and regulatable timing means for varying the timing of injection according as the operating needs of the engine may require.

Still another object is to provide a device as above described, which is equally applicable to reversing types of internal combustion engines as well as to non-reversing engines.

The terms employed herein are used in the generic and descriptive sense to designate the elements illustrated, and are therefore not specifically intended as terms of limitation.

Referring to the accompanying three (3) sheets of drawings:

Fig. 1 diagrammatically represents an engine equipped with my device.

Fig. 2 represents a right elevational view of Fig. 1, showing some of the operating mechanisms of my device in section.

Fig. 3 represents a sectional view taken on line 3—3 Fig. 2, showing the discharge regulating means in mid-position and the pump in its suction stroke.

Fig. 4 represents a similar view to Fig. 3 but shows the pump plunger in its extreme "up" position.

Fig. 5 represents a sectional view taken on line 5—5, Fig. 4.

Fig. 6 represents an enlarged sectional view taken on line 6—6, Fig. 4.

Fig. 7 represents a sectional view taken on line 7—7, Fig. 3.

Fig. 8 represents the same view as Fig. 3 but shows the discharge regulating means in set position for "minimum" discharge and the pump plunger in its "up" stroke.

Fig. 9 represents a part sectional view taken on line 9—9, Fig. 10.

Fig. 10 is a similar view to Fig. 8 but shows the discharge regulating means set for "maximum" discharge.

Like numerals refer to like parts throughout the several views of the drawings.

The numeral 20 represents in its entirety a high pressure oil engine in which 21 is the power cylinder, 22 the crank-shaft and 23 a type of spray nozzle ordinarily used for the solid injection of liquid fuels, which discharges into the combustion chamber 24 of the cylinder.

25 represents a rigid guide member which may be made integral with an engine part, as the base, or rigidly secured thereto, according as may be desired. 26 is a supply base or reservoir for the pump casing 27 which is provided with the pump chamber 28 communicating with the supply chamber 29 of the supply base 26 through the automatic suction valve 30 which is preferably of the non-return type. The pump casing 27 is preferably provided with the bores 31 and 32 in the former of which is slidably fitted the supporting and adjusting guide-member 33 which rides on the regulating eccentric 34 operating within the pump chamber 28. The pump casing 27 is preferably provided with the slots 35 and 36 through which the floating-lever 37 operates and which lever is pivotally secured at one end to the forked guide member 33, as shown, with the other end projecting freely within the bore 32, and is normally held in the down position by the light expansion spring 38 provided for the purpose, as shown in Fig. 3. 40 represents a tapered pump-plunger bushing which is secured to the casing 27 in the tapered section provided therefor by the take-up gland 41 which is screwed to the casing 27 and provides a stuffing box about the floating or impulsion type of pump plunger 42 as shown. The plunger is intended to work reasonably free through said stuffing box so as not to interfere unduly with the action of its intermediary impulsion drive, as will be ex-

100
105
110

plained hereinafter. The tapered member 40 is perforated with the transverse holes 43 which register with the main discharge casing ports 44 and 45.

- 5 The regulating eccentric 34 is preferably made integral with the spindle 46 which rotatably operates within the gland 47 through the regulating arm 48 which is secured to said spindle 46. The top of the 10 casing 27 is provided with the auxiliary relief valve plug 50 which is rigidly secured thereto and which in turn is provided with the relief valve 51 which seats at 52 and has its spindle 53 extending into the pump 15 chamber 28 and positioned in the plane of the floating-lever 37 for engaging therewith, as will be hereinafter explained. The plug 50 is provided with the intake and discharge ports 54 and 55, respectively, and 20 houses the impulsion spring 56 which acts against the valve 51 to seat the same normally through the guide spindle 57, and is adjustable through the adjusting screw 58. The plug 50 is enclosed within the casing 59 25 which receives the discharge from the port 55 and ushers the same into the return pipe 60 through the return recess 61 provided therefor in the casing 27. The casing 59 is held secured in position with the casing 27 30 by the nut 62 which also serves to lock the adjusting screw 58 into set position with the plug 50.

Within the rigid guide member 25 operates the reciprocating pump member 63 35 which houses the expansion spring 64, acting against the floating pump plunger 42 through the slidible guide plug 65 and is provided with the arced shoe or link block 66 which may be rigidly secured thereto 40 or made integral therewith, according as may be desired. The floating pump plunger 42 is provided with the valve recess 67 towards the top end thereof, while the lower end is provided with the shoulder or flange 45 68 which floatingly couples the plunger 42 with the reciprocating member 63 through the regulatable coupling member 69 which is adjustably secured to said reciprocating member 63 as shown. 70 represents a stop 50 rod to limit the spring deflection and is housed within said reciprocating member 63 and is preferably rigidly secured thereto.

In the construction shown the arced shoe 66 slidably carries the timing and reversing arc or link sector 71 which is pivotally coupled at 72 with the operating eccentric member 73 which is actuated by the eccentric 74 keyed or otherwise coupled preferably to the crank-shaft 22 for rotating 60 therewith.

The arc 71 is pivotally coupled to the connecting link 75 which in turn is pivotally coupled to the operating lever 76 which is fulcrumed at 77 to the notched or toothed 65 arc 78 to which the lever 76 may be locked

into set position through any suitable locking means, as the spring-held latch shown in Fig. 1 for example. It is apparent that instead of the described link construction, the same results may be attained by means of a 70 Stephenson or similar type of reversing gear to change the stroke of the reciprocating plunger 42 and provide for varying the timing of the main discharge port 44.

The main discharge port 45 of the pump 75 casing 27 connects with the injecting valve 23 by means of the pipe 80, and the injecting valve is provided with the check-valve 81, the spiral accelerator 82 and the discharge opening 83 which is open to the combustion chamber 24 of the cylinder 21.

85 and 86 represent the supply and overflow pipes, respectively, for the supply chamber 29.

87 represents a connecting link which may 85 be pivotally coupled at one end to the arm 48, and if desired connects said arm with the governing mechanism (not shown) of the engine for automatically adjusting the 90 regulating eccentric 34 according to the speed of the engine.

Having thus described the parts of my invention in detail, the manner in which the same operates is as follows:

First, it will be observed that the setting 95 of the timing lever 76 in the full line position shown in Fig. 1 for forward running of the engine indicated by the arrow marked "F", yields a cracking or opening of the plunger valve when the eccentric center "C" 100 reaches a point in advance of the head end dead center position as shown in Figs. 1 and 8. Therefore, it must be understood that any setting of the timing lever 76 between the full line position shown in Fig. 1 and the 105 dotted position shown in said figure and indicated "X" for forward running of the engine, will yield an earlier cracking of the plunger valve of the device than that occasioned by the full line setting of said lever 76 and similarly it follows for forward running of the engine that any setting of the lever 76 beyond the full line position shown in Fig. 1 in the opposite direction on the arc or quadrant 78 (as for example the dotted position "Y") will retard the time of 110 opening of the plunger valve of the device and will allow for a later injection.

For reverse running of the engine indicated by the arrow marked "R", Fig. 1, the 115 full line position shown in said figure will yield the same relative time of opening for the plunger valve as occurs in forward running of the engine, but advancing the lever towards the "X" position will yield "late" injection, while advancing the lever 120 towards the "Y" position will yield a "leading" or "earlier" injection.

Assuming for example that the compression pressure in the combustion chamber 24 125

is 300 lbs. against which my device injects the liquid fuel and that the desired pressure to be maintained in the pump chamber 28 is set at say 2000 lbs. per sq. inch or over, then it will be understood that a suitable spring 56 must be employed sufficient to hold the valve 51 seated against the pressure required in the pump chamber 28. The spring 64 must be designed to cause the same to compress under the desired pressure in the pump chamber 28 (as shown in Fig. 8), but in any event must be sufficiently stiff to furnish the impelling kick to the plunger 42 such that the spring drives said plunger beyond its normal limit of discharge-stroke travel provided by the rigid pushing or driving means of the reciprocating member 63.

It will be here understood that the relief valve 53 is relatively small and therefore the spring 56 is comparatively light but sufficient nevertheless to withstand the desired pressure in the pump chamber, while on the other hand the spring 64 is relatively stiffer and capable of forcing the plunger 42 to lift the relief or auxiliary discharge valve 51 through the floating lever 37 against the pressure of the spring 56. It will also be understood that the port 54 leading to the bleeder valve seat 52 is preferably so located as to take off any entrapped air that may accumulate at the highest point in the pump chamber and thus prevent the plunger from becoming air bound.

The regulating arm 48 which operates the eccentric 34 may be hand-operated if desired, and may be provided with locking means, as a notched locking arc (not shown) for holding the same in set position. It is preferable, however, wherever possible to couple said arm 48 with the governing mechanism (not shown) of the engine, as by means of the link 87, for automatically regulating the supply eccentric according to the engine load; the arm 48 having a radius of action from the minimum supply position, represented by the dotted position of the arm, Fig. 9, which corresponds to the eccentric setting in Fig. 8, to the maximum supply position shown in Fig. 9 (full lines) which corresponds to the eccentric setting shown in Fig. 10.

Now assuming that the engine is operating in the forward direction, represented by the arrow marked "F" Fig. 1, with the timing lever set in mid or full line position shown in said figure, that the regulating eccentric is set in the mid position corresponding to the setting shown in Figs. 3, 4 and 7, and also that the supply chamber 29 is kept supplied with liquid fuel under a fixed initial pressure head, then the device operates in the following manner: The suction stroke, as is understood, is the down

stroke of the reciprocating member 63 which is actuated by the eccentric member 73 and carries the floating plunger 42. Fig. 3 shows the device in the suction stroke, where it will be noted that the plunger and relief valves are both closed, while the suction valve 30 is open; it will also be noted that the valve lifting lever 37 is clear of and out of contact with the relief valve stem 53 and that the spring 64 is expanded so that the flange 68 of the plunger 42 is in the extreme "up" position and is being held against the coupling member 69 as shown. The suction stroke of the device fills the pump chamber 28 with the liquid fuel used to operate the engine. As soon as the reciprocating member 63 completes its suction stroke it starts on its compression or "up" stroke as shown in Figs. 8 and 10, and the suction valve 30 closes. In this compression stroke of the device it will be noted that the pressure in the pump chamber rises to the required point (say 2000 lbs.) beyond which but previous to the opening of the plunger or main discharge valve of the device, the auxiliary or relief valve 51 (because of the incompressibility of the liquid in the closed pump chamber 28) is caused to unseat (Fig. 10) sufficient to allow a bleeding action to take place, resulting in a limited discharge through the port 55 of the plug 50, from where the discharge drains back through the pipe 60 to the main oil supply reservoir (not shown). During this period of the compression stroke, it will also be noted that the fluid pressure load on plunger 42 acting through the slidible guide plug 65 causes the spring 64 to compress as shown in Fig. 8, leaving the free space "K" between the flange 68 of the plunger 42 and the coupling member 69 for the supplemental reaction or kick of the plunger, which will be more fully explained.

It is further pointed out that the spring 63 is to be made stiff enough to carry the oil pressure load imposed upon the plunger without excessive deflection and that the plug 65 should not be allowed to bottom upon the stop rod 70 before the maximum desired pressure has been reached in the pump chamber, thus at all times keeping said spring fully balanced with respect to the oil pressure load acting on the plunger. The stop rod 70 is intended to protect the spring 63 against impairment of its elasticity from overload. It is apparent that by the use of a relatively stiff spring, its deflection may be still properly limited so as to hold the plunger in its required position for the purposes intended, even though the stop rod 70 is entirely dispensed with.

The position of the plunger 42 and the reciprocating member 63, as shown in Fig. 8, corresponds to the position of the driving eccentric 74 shown in Fig. 1, in which view

it will be seen that the center "C" of the eccentric 74 for forward or "F" running direction of the engine is approaching its dead center position but in advance of said 5 head dead center position, and in that position (as shown in Fig. 8) the plunger or main discharge valve is just cracking open. Therefore, the remainder of the eccentric stroke will lift the plunger 42 the short distance "L" on the eccentric circle (Fig. 8), during which lift the plunger valve will remain open. With the opening of the plunger valve, which opens the pump chamber to the engine cylinder, the auxiliary or relief valve 51 automatically closes and stops the bleeding action above referred to and the oil in the pump chamber, which is under a much higher pressure than the pressure in the combustion chamber, forces its way 20 through the pipe 80 and is finally injected in spray form at a high velocity into the combustion chamber 24 through the injection nozzle 23. Thus it will here be observed that the device is designed to provide a 25 positive opening of the main discharge valve of the pump under the direct action of the operating eccentric 74, as already explained.

Supplementary to that action the device 30 is designed to prolong the period of opening of the plunger valve beyond the aforesaid normal period, together with a further accelerating drive on the oil discharge through the plunger valve by the occurrence of an additional length of stroke to the pump plunger which is due to the independent reaction of the spring 64 in the reciprocating member 63, taking place in the shape of a kick against the plunger 42 35 through the distance "K" (Fig. 8) when the reciprocating member 63 nears or reaches the top of its stroke. It will thus be here noted that the plunger 42 is of the impulsion type and that the same is actuated directly 40 in the first instance on its compression and discharge stroke by the operating eccentric 74, and that in addition thereto it is further actuated during said stroke by the reaction or expansion of the spring 64 which kicks 45 against it with appreciable force and provides the functions above stated.

The steady high pressure behind the spray nozzle resulting from the "follow-up" action of the auxiliary resilient plunger drive, 50 maintains a highly uniform rate of liquid flow during the entire nozzle discharge period and thus assures a far more perfect spray formation into the power cylinder than would otherwise be attainable with an integral direct plunger drive.

The described plunger-kick offers the further advantage of effecting a good spray action with a commercially practicable nozzle orifice of say 1/64 or larger, even in engines 55 of relatively small bore dimensions.

The amount of liquid forced through the main discharge valve 44 is dependent upon the simultaneous plunger displacement resulting from the actuating gear movement and the supplementary plunger "kick". In 70 a variable speed engine it is preferred to impart the major portion of the plunger displacement required at slow speed by means of the plunger "kick," while at the higher speeds the actuating gear may be 75 made to contribute a larger component of the resultant plunger displacement.

When the spring 64 is compressed by the load imposed on the plunger by the predetermined chamber pressure as previously described, it will be apparent that the opening of the discharge valve affords a second independent outlet for the high pressure maintained within the pump chamber prior to the discharge period. Such second pump 80 outlet discharging to the nozzle offers a far lower resistance to the oil than does the loaded bleeder valve when set for a high predetermined pressure. As a result of 85 opening the discharge valve, the pump chamber pressure will drop somewhat, thus automatically closing the bleeder valve 51 which in turn starts the release of the energy 90 stored in the spring 64 and allows it to impart its characteristic impulse to the plunger part. The spring force rapidly drives the plunger forward and ahead of its retarded gear position whereby the resulting 95 impulse or "kick" is made to accelerate the plunger movement with respect to the rigid 100 actuating gear movement.

Due to the yielding drive, the rate at which the plunger is allowed to surge forward is primarily fixed by the restricted 105 discharge capacity of the nozzle, and is not therefore limited to the velocity imparted by the rigid actuating gear movement.

The initial pressure maintained behind the nozzle will be slightly lower than the predetermined pressure fixed by the bleeder 110 valve, and this will continue to drop somewhat as the restricted nozzle discharge allows the yielding drive to recover. Since the displacement capacity of the "kick" is intended to exceed the normal or rated discharge capacity of the pump, it will be further evident that during the major portion 115 of the discharge period, the yielding plunger drive serves to crowd the nozzle to the utmost of its discharge capacity and so maintains a nearly uniform discharge pressure behind the nozzle during the entire injection period.

It is emphasized that within the range of 120 its rated capacity, my fuel pump is intended to utilize only the initial or effective portion of its impulsion stroke for the purpose of injecting fuel into the engine cylinder. The end portion of said stroke is 125 purposely discarded. After the pump delivery 130

pressure has dropped to a point where it is still fairly high but no longer capable of producing the desired effective atomization of the injected fuel, the chamber pressure 5 is sharply interrupted by means of the bypass valve which then cuts off the fuel delivery to the fuel injection nozzle. This valve serves as a supplementary vent for the air that may have been entrained or 10 entrapped in the liquid fuel passages and to rid the pump of the pernicious air effects. Unless this is prevented, the pump would continue to deliver imperfectly atomized fuel to the injection nozzle until the 15 confined air pressure had entirely spent itself, notwithstanding that the plunger may already have partially completed its return or suction stroke. By virtue of the described pressure control means, it becomes possible 20 to accurately terminate the period of fuel injection into the engine cylinder when working with the impulsion type of pump plunger.

Furthermore, the fact that the rate of 25 nozzle discharge is not primarily dependent upon the actuating gear movement allows a pump of this kind to be run at slow piston speeds without impairing its atomizing capacity, and in the case of a four-stroke engine, it is possible to operate the pump at 30 half engine speed in unison with the cam shaft and still get a proper nozzle action at all speeds of the engine.

It is further pointed out that in my high-pressure pumping device, a considerably 35 larger amount of oil is sucked from the supply reservoir 26 than is ultimately sent forth to the engine cylinder. The purpose of this excess plunger displacement is two-fold: First, to insure sucking in a surplus amount of solid oil into the pump at all 40 speeds after allowing for any air that may be entrapped with the oil and for sluggish lifting of the suction valve; and secondly, to allow subjecting the oil to a predetermined high pressure prior to the discharge 45 valve opening.

In connection with the above supply and 50 spraying action of the device, it will now be explained how the device is further designed to automatically cut-off the spray to the cylinder (when the charge in the cylinder becomes sufficient) with a marked degree of suddenness, whereby it becomes 55 impossible for the spray to form into drips at the end of the spraying period. This sudden cut-off action of the spray, is accomplished through the forced opening of the auxiliary or relief valve 51, as is occasioned 60 through the lifting of the floating lever 37 by the plunger 42 (Fig. 4), whereupon the pump chamber 28 is suddenly opened to atmospheric pressure (that being the pressure 65 in the pipe 60) and the oil therein immediately starts to flow through the auxiliary

or relief valve against said atmospheric pressure, instead of the much higher pressure of the combustion chamber. This results in setting up a sudden and sharp drop in pressure in the pipe connections leading 70 to the spray nozzle and eliminates the drip formation to the high pressure in the spray which otherwise occurs when the spray valve pipe connection is allowed to die down instead of being suddenly relieved. 75

In an internal combustion engine in which fuel oil is injected by means of a high pressure pump, pipe lines of considerable length are usually required to carry the oil to the spray nozzle. Such pipes 80 not only contract appreciably when being relieved of high pressure, but owing to the entrapped air that is usually carried along with the liquid fuel, there is still a marked tendency in pumps of usual construction 85 for the pipe line pressure to persist after the pump chamber has been relieved of its pressure.

In my improved construction, the mechanically operated discharge valve is positively held open while the pump chamber 90 is being relieved of pressure, whereby a direct communication is maintained during this period between the nozzle pipe and the relatively liberal vent area afforded by 95 the relief valve 51. The interval and extent of the spraying action and the point of cut-off to the spray is governed by the setting of the regulating eccentric 34 which varies the position of the fulcrum point of 100 the floating-lever 37. The lower the fulcrum point (as Fig. 10) the later the relief valve is forced open by the pump plunger 42 and consequently the longer the period of spray and the later the point of 105 cut-off; while the higher the fulcrum point of the floating-lever 37 (as Fig. 8) the earlier the opening of the valve 51, resulting in the shorter period of spray and an earlier point of cut-off of pressure in the 110 spray valve connection.

It will thus be observed that by coupling the regulating eccentric 34 with the governing mechanism of the engine that automatically the device will adjust itself to suit 115 the needs of the engine as to fuel supply. The fluid discharge sent forth to the engine cylinder is accurately measured by the combined plunger "kick" and actuating displacement which is allowed to occur between 120 the time of opening the main discharge port 44 and the lift of the relief valve 51. Two distinct means are provided which allow of regulating the oil discharge from the pump, one residing in the variable timing given 125 by the main discharge valve by the link sector 71, and the other residing in the floating lever 37.

It will also be observed that the auxiliary 130 relief or discharge valve 51 acts in a dual

capacity; in one case it acts as a bleeder while the plunger 42 is in its delivery stroke and previous to the opening of the plunger valve, while in the other case it acts to cut off the spray at the desired time when the plunger or main discharge valve is open.

It is apparent that each of the described dual functions of the combined bleeder and relief valve 51 may, if desired, be readily 10 performed by two separate valves, one such serving primarily in the distinct capacity of a bleeder valve to maintain a predetermined pressure in the pump chamber, while an independently seated auxiliary relief 15 valve, also bypassing the oil to the supply reservoir, may be used to perform the regulating functions for the pump discharge by breaking the pressure at the spray nozzle at a definite but variable point in the 20 plunger discharge stroke. Any suitably actuated relief valve, controlling the communication between the nozzle pipe line 80 and the supply reservoir 26, may be used for this latter purpose, in which case such 25 valve remains seated and does not function until after the discharge valve has been opened.

It is further pointed out that the bleeder function of the valve 51 is not an essential 30 element in the described type of fuel pump. It will be evident that the bleeder function of said valve may, if so desired, be eliminated since the resilient plunger drive of itself affords a large measure of safety 35 against an excessive pressure arising in the pump chamber. Such a drive at the same time provides a suitable means for securing a predetermined maximum pressure within the pump chamber prior to the opening of 40 the discharge valve, without necessarily resorting to the use of a bleeder valve for this purpose.

It will also be observed that the valve 51 acts as a safety valve for the device, should 45 the injecting nozzle 23 become clogged through any cause; the spring 56 is adjustable through the adjusting plug 58 and the lock nut 62 may be removed even during the operation of the device to check up the 50 working functions of the same without stopping the engine. The device may be made up as substantial as may be necessary to suit the particular uses to which the same may be put, and is absolutely reliable and practical, 55 overcoming many of the heretofore objectionable features common to the ordinary devices used for the purpose, and therefore supplies a long-felt want in the art.

Finally, it is pointed out that a further 60 important feature of present invention resides in the discharge valve control for releasing the impulsion energy stored behind the plunger as used in combination with a bypass device adapted to interrupt the pump

chamber pressure. This arrangement admits of breaking the pump chamber pressure either subsequent or prior to the discharge valve opening and hence an effective and positive plunger ram action is produced irrespective of the relative pump delivery 70 through the discharge valve. In the present instance, the discharge valve and passages leading to the cylinder nozzle may be unrestrictedly opened at any predetermined period and the pump will continue to freely 75 deliver therethrough within its rated capacity up to such time that the bypass becomes operative, whereupon the effective pump delivery will be interrupted although the discharge valve may still remain wide open. 80 This improved mode of operation represents a distinct advance over such types of fuel injectors in which the termination of the plunger delivery is made dependent upon 85 the timed closure of the discharge valve element; this latter type of pump involves injecting its fuel delivery through a restricted and partially opened release control for the resilient plunger, which in turn, makes the resulting plunger kick sluggish 90 and less effective, particularly so at light engine loads.

While the preferred embodiments of my invention have been described in detail, it 95 will be understood that I do not wish to be limited to the particular construction set forth, since various changes in the form, material, proportions, and arrangement of parts, and in the details of construction may be resorted to without departing from the spirit and scope of the invention or destroying any of the advantages contained in the same, heretofore described and defined in the subjoined claims.

Having thus described my invention in 105 detail, what I claim as new is:

1. A pump comprising a plunger, a suction valve and a positively opened discharge valve, a relatively rigid actuating gear for reciprocating said plunger, an intermediary resilient drive adapted to yield against said plunger during a portion of the discharge stroke movement of the actuating gear, means for opening said discharge valve to allow said drive to recover and impel the plunger onward, and means adapted to utilize only the initial portion of the impulsion stroke for the effective pump delivery through said discharge valve.

2. In an internal combustion engine in which liquid fuel is injected into a charge of compressed air held within the power cylinder, a fuel pump having a suction and a positively opened discharge valve, a reciprocating actuating part and a driven plunger part, an impulsion drive acting between said parts, means to store impelling energy during a portion of the discharge stroke of the

actuating part, means for opening said discharge valve to quickly release said energy and inject liquid fuel into the power cylinder, and control means adapted to interrupt the pump delivery through said discharge valve prior to the closure thereof.

3. In a reciprocating pump having a suction valve, a positively opened discharge valve and a plunger part, a relatively rigid actuating gear, an intermediary resilient drive for the plunger part, a bleeder valve to maintain a predetermined pressure within the pump chamber and serving to store energy in said resilient drive during a portion of the discharge stroke of the actuating gear, and means for opening the discharge valve to release said energy and impel the plunger part onward.

4. In a reciprocating pump having a suction valve, a positively opened discharge valve and a plunger part, a relatively-rigid actuating gear, an intermediary resilient drive for the plunger part, a loaded bleeder valve maintaining a predetermined pressure within the pump chamber and serving to store impelling energy in said resilient drive during a portion of the discharge stroke of the actuating gear, means for opening the discharge valve to release said energy and impel the plunger part onward, and control means for unloading the bleeder valve at a definite but alterable point in the plunger discharge stroke.

5. In a pump having a plunger part and a positively opened discharge valve, a relatively stiff actuating gear for reciprocating said plunger part, an intermediary resilient drive adapted to yield during the plunger discharge stroke; means for opening said discharge valve to impel the plunger part onward, means for returning the plunger part with the actuating gear, and bypass means adapted to interrupt the pump delivery.

6. In a pump having a reciprocating plunger member, a relatively stiff actuating gear, a resilient drive, means for storing impulsion energy within said drive during each discharge stroke movement of the actuating gear, a discharge valve adapted to release said energy, a valve gear means for opening said valve, and control means for variably timing the opening of said valve.

7. In a pump comprising a plunger and a chamber having an inlet and a discharge valve, a relatively stiff actuating gear adapted to reciprocate said plunger, means for positively opening said discharge valve, an auxiliary resilient drive adapted to act against said plunger during the latter portion of its discharge stroke for subsequently impelling the plunger onward to effect a more rapid rate of discharge during the latter part of its stroke, and control means

adapted to interrupt the pump delivery through said discharge valve prior to the closure thereof.

8. In a pump comprising a recessed plunger member and a chamber having an inlet valve and a plunger controlled discharge port, a relatively stiff actuating gear adapted to reciprocate said plunger member and to register the recess thereof with said discharge port and provided with an auxiliary resilient drive adapted to yield prior to the registering of said plunger recess and serving to supplementally impel said plunger onward to maintain a more nearly uniform rate of pump discharge.

9. In a pump comprising a recessed plunger member and a chamber having an inlet and a plunger controlled discharge port, a relatively stiff actuating gear adapted to reciprocate said recessed plunger member and to register the recess thereof with said discharge port, an auxiliary resilient drive adapted to yield prior to the registering of said plunger, and means for variably timing the opening of said discharge port.

10. In a pump comprising a plunger and a chamber having an inlet and a positively opened main discharge valve, a relatively stiff actuating gear adapted to reciprocate said plunger, an intermediary resilient drive for said plunger adapted to yield prior to the opening of the main discharge valve, and an auxiliary or bleeder valve serving to maintain a predetermined pressure in the pump chamber prior to the opening of the main discharge valve.

11. In a pump comprising a plunger and a chamber having an inlet and main discharge valve, a relatively stiff actuating gear adapted to reciprocate said plunger, an auxiliary or bleeder valve serving to maintain the pump chamber at a predetermined pressure, an intermediary resilient drive adapted to yield against said plunger during a portion of its discharge stroke and for accelerating the rate of pump discharge during the latter part of the discharge stroke through said main discharge valve, and means for closing said bleeder valve during said discharging period.

12. In a pump comprising a plunger and a chamber having an inlet and a main discharge valve, a relatively stiff actuating gear adapted to reciprocate said plunger, an auxiliary resilient drive adapted to provide the plunger with a limited yielding action during a portion of its discharge stroke, a combined bleeder and relief valve serving in the first instance to maintain the pump chamber at a predetermined pressure and subsequently as an auxiliary discharge for said pump, means for opening the main discharge valve, and means for opening said combined valve to relieve the pump chamber of pres-

sure and to interrupt the discharge through the main discharge valve.

13. In a pump comprising a plunger and a chamber having an inlet and main discharge valve, a relatively stiff actuating gear adapted to reciprocate said plunger, an auxiliary resilient drive, a combined bleeder and relief valve serving in the first instance to maintain a predetermined pressure in the pump chamber, means for opening the main discharge valve, means for opening the combined valve to relieve the chamber of pressure, and a control means for variably timing said combined valve opening means and adapted to regulatably measure the fluid discharge through the main discharge valve.

14. In a pump comprising a reciprocating plunger and a chamber having an inlet and a main discharge valve, a combined bleeder and relief valve serving in the first instance to maintain a predetermined pressure in the pump chamber, means for opening the main discharge valve and simultaneously closing the bleeder valve, and means for opening the combined valve to break the pressure in said pump chamber and interrupt the discharge through the main discharge valve.

15. In a pump of the character described, a casing member having a supply chamber communicating with a pump chamber provided with an inlet, a main outlet and an auxiliary outlet, communicating with said supply chamber, a plunger having a flexible connection with an actuating gear therefor provided with means for porting said main outlet, means for normally closing said auxiliary outlet, means for mechanically opening said auxiliary outlet, and means for regulating the time of opening of said auxiliary outlet.

16. In a pump of the character described, a casing member having a supply chamber, a pump chamber communicating with said supply chamber and provided with an inlet, a main outlet and a by-passing auxiliary outlet coupled with said supply chamber, a floatable plunger provided with means for porting said main outlet, automatic means for normally closing said auxiliary outlet, means for mechanically opening said auxiliary outlet, means for regulating the time of opening of said auxiliary outlet, and means for actuating said floatable plunger.

17. In a pump of the character described, a casing member having a pump chamber communicating with a supply chamber and provided with an inlet, a main outlet and an auxiliary outlet communicating with said supply chamber, a floatable plunger provided with means for porting said main outlet, means for normally closing said auxiliary outlet, means engaging with said plunger for opening said auxiliary outlet, means for variably setting the latter means for regulating the time of opening of said auxil-

iary outlet, means for actuating said floatable plunger, and yieldable energizing means for said actuating means for furnishing a recovering impulse to the plunger.

18. In a pump of the character described, a casing member having a pump chamber provided with an inlet valve, a main plunger valve outlet open to an injecting nozzle, and an auxiliary outlet open to the source of supply, a pump plunger operating in said pump chamber provided with a valve control for said main outlet, a driving member provided with rigid and yielding pushing means adapted to engage with said pump plunger, a coupling member floatably connecting said pump plunger with said driving member, a valve normally closing said auxiliary outlet, an auxiliary valve lever adapted to be operated by the pump plunger for opening said auxiliary outlet valve, a moveable pivoting member carrying the pivoted end of said lever, and means for changing the position of said moveable pivoting member.

19. In a pump of the character described, a casing member having a pump chamber provided with an inlet valve, a main plunger valve outlet open to an injecting nozzle, and an auxiliary outlet open to the source of supply, a pump plunger operating in said pump chamber provided with a valve control for said main outlet, a driving member provided with rigid and yielding pushing means adapted to engage with said pump plunger, a coupling member floatably and regulatably connecting said pump plunger with said driving member, a valve normally closing said auxiliary outlet, an auxiliary valve lever adapted to be operated by the pump plunger for opening said auxiliary outlet valve, a moveably pivoting member carrying the pivoted end of said lever, means for changing the position of said moveably pivoting member, means for actuating said driving member, and means for varying the timing operation of said pump plunger.

20. In a pump having a plunger member, a relatively stiff actuating gear for reciprocating said plunger member, an auxiliary resilient drive adapted to yield against said member during a portion of the discharge stroke thereof, means subsequently allowing said drive to recover and impel the plunger member onward, and means to control said plunger impulse.

21. In a pump comprising a plunger member and a chamber having an inlet and a discharge valve, a relatively stiff actuating gear adapted to reciprocate said plunger, an auxiliary or bleeder valve serving to maintain the pump chamber at a predetermined pressure, an auxiliary resilient drive adapted to yield against said plunger during a portion of its discharge stroke, means subse-

quently allowing said drive to recover and impel said plunger onward to accelerate the pump discharge through the discharge valve, and means for closing said bleeder valve during said discharge.

22. In a fuel pump for an internal combustion engine, comprising a plunger and a chamber having a suction and discharge valve, a relatively rigid actuating gear 10 adapted to reciprocate said plunger, operating means for positively opening said discharge valve, an auxiliary resilient drive adapted to yield against said plunger during a portion of its discharge stroke, and 15 regulating means for changing the opening of said discharge valve with respect to the end of the actuated plunger stroke to variably impel the plunger onward and regulate the fuel discharge from the pump.

23. In a reciprocating pump comprising a positively opened discharge valve, a driven plunger part and an actuating part, a spring drive connection between said parts, means for compressing said spring during a portion of the discharge stroke movement of the actuating part, control means for opening said discharge valve to release said spring and impel the plunger part onward, said spring being brought to substantially 25 the same degree of compression prior to its release irrespective of the pump delivery through said discharge valve.

24. In a reciprocating pump comprising a positively opened discharge valve, a driven plunger part and an actuating part, a spring drive connection between said parts, means for compressing said spring during a portion of the discharge stroke movement of said actuating part and for opening said discharge valve to release said spring and control means for limiting the effective impulsion movement of said parts with respect to each other.

25. In a reciprocating pump having a suction and a positively opened main discharge valve and comprising a driven plunger part and an actuating part, a spring drive connection between said parts, an auxiliary bleeder valve to maintain a predetermined pressure within the pump chamber and serving to compress said spring during a portion of the discharge stroke of the actuating part, and means for subsequently opening the main discharge valve to release said spring.

26. In an internal combustion engine, a reciprocating fuel pump having a suction and a discharge valve and a plunger, a spray nozzle for admitting fuel into the power cylinder, a conduit connecting the discharge valve with the spray nozzle, an auxiliary valve adapted to relieve said conduit of pressure to prevent dripping at the nozzle, means for opening said auxiliary valve at a definite but variable point in the

plunger discharge stroke, and means for holding open the discharge valve during the opening period of said auxiliary valve.

27. In a reciprocating pump comprising a suction valve and a supply reservoir therefor, a positively opened discharge valve, a driven plunger part and an actuating gear part, a spring drive between said parts, means for compressing said spring during a portion of the discharge stroke of said actuating part, means for opening said discharge valve to release said spring and to impel said plunger part onward, an auxiliary relief valve adapted to bypass into said reservoir and serving to interrupt the pump discharge, a lever adapted to open said relief valve, having a protruding part projecting into the path of said plunger part, and regulatable means for striking said protruding part in a definite but alterable point in the path of said impelled plunger part.

28. In a reciprocating pump comprising a suction valve and a supply reservoir therefor, a positively opened discharge valve, a driven plunger part and an actuating gear part, a spring drive between said parts, means for compressing said spring during a portion of the discharge stroke of said actuating part, and means for opening said discharge valve to release said spring and to impel said plunger part onward; an auxiliary relief valve adapted to bypass into said reservoir and serving to interrupt the pump discharge; a floating lever adapted to open said relief valve, said lever having an end portion projecting into the path of the plunger and adjusting means at its other end portion adapted to alter the position at which said lever opens said auxiliary relief valve.

29. In a reciprocating pump comprising a suction valve and a supply reservoir therefor, a positively opened discharge valve, a driven plunger part and an actuating gear part, a spring drive between said parts, means for compressing said spring during a portion of the discharge stroke of said actuating part, and means for opening said discharge valve to release said spring and impel said plunger part onward, an auxiliary relief valve adapted to bypass into said reservoir and serving to interrupt the pump discharge, and mechanical means operating in unison with the plunger part to open said relief valve subsequent to said spring release.

30. In a reciprocating liquid fuel pump comprising a suction valve and a supply reservoir therefor, a positively opened discharge valve, a driven plunger part and an actuating gear part, a spring drive between said parts, means for compressing said spring during a portion of the discharge stroke of said actuating part, and means for

opening said discharge valve to release said spring and to impel said plunger part onward, an auxiliary relief valve adapted to bypass into said reservoir and serving to 5 interrupt the pump discharge, mechanical means operating in unison with the plunger part to open said relief valve and governing means for the last named mechanism to control the delivered pump discharge resulting 10 from the combined gear and impulse movement imparted to said plunger part.

31. In a reciprocating fuel pump comprising a suction valve and a supply reservoir therefor, a positively opened main discharge valve, a driven plunger part and an actuating gear part, a spring drive between said parts, means for compressing said spring during a portion of the discharge stroke of said actuating part and means for 15 opening said discharge valve to release said spring and impel said plunger part onward, and an overflow means to maintain an initial pressure head within said supply reservoir.

32. In a reciprocating liquid fuel pump discharging to a spray nozzle, a suction valve and a supply reservoir therefor, a pump chamber adapted to pump an excess quantity of liquid fuel during each stroke, 20 a positively opened discharge valve communicating with said nozzle, a driven plunger part and an actuating gear part, a spring drive between said parts, means including a bleeder valve to maintain a predetermined 25 pressure in the pump chamber and serving to compress said spring during a portion of the discharge stroke of said actuating part, said bleeder valve further serving to return the excess portion of such excess liquid fuel 30 to said reservoir, means for subsequently opening said discharge valve to release said spring and impel the plunger onward whereby a portion of the remaining fuel is sent forth to said nozzle, and regulating 35 means for variably interrupting the nozzle discharge.

33. In a pump having a chamber and a suction and a discharge valve therefor, a

nozzle, a conduit delivering to said nozzle, a controlled relief valve adapted to relieve 50 the delivery pressure behind said nozzle and prevent dribble, means for opening said relief valve, and means for periodically establishing communication between said chamber and the nozzle during such relief period. 55

34. In a pump comprising a plunger, a discharge valve, a nozzle, a conduit delivering from said discharge valve to the nozzle, a driven plunger part and an actuating part, a spring drive acting between said parts, 60 means for compressing said spring during a portion of the discharge stroke of the actuating part, means for opening the discharge valve to release said spring and impel the plunger onward, and a bypass valve 65 adapted to relieve the delivery pressure behind said nozzle and prevent dribble.

35. A pump comprising a plunger member, a suction valve and a discharge valve, a relatively rigid actuating gear for reciprocating said plunger member, an intermediary resilient drive adapted to yield against 70 said plunger member during a portion of the discharge stroke movement of the actuating gear means allowing said drive to recover and impel the plunger member onward, and control means serving to interrupt the pump delivery pressure prior to the end 75 of the impulsion stroke.

36. In a fuel pump comprising a reciprocating actuating part and a driven part, an impulsion drive acting between said parts, means for storing energy within said drive during the discharge stroke movement of the actuating part, means including a 80 discharge valve adapted to release said energy and allow of impelling the plunger onward to superimpose an augmented rate of movement upon the plunger part, and control means adapted to interrupt the pump delivery through said discharge valve prior 85 to the closure thereof.

In testimony whereof, I have hereunto set my hand this fifteenth day of April, 1918.

LOUIS ILLMER.
